UNITED STATES PATENT OFFICE.

JAMES MORRIS, OF STREATOR, ILLINOIS, ASSIGNOR TO STREATOR METAL STAMPING COMPANY, OF STREATOR, ILLINOIS, A CORPORATION OF ILLINOIS.

TOP-BUGGY.

No. 821,727.

Specification of Letters Patent.

Patented May 29, 1906.

Application filed August 20, 1904. Serial No. 221,498.

To all whom it may concern:

Be it known that I, JAMES MORRIS, a citizen of the United States, and a resident of Streator, in the county of LaSalle and State 5 of Illinois, have invented certain new and useful Improvements in Top-Buggies, of which the following is a specification, reference being had to the accompanying drawings.

10 My invention relates to improvements in top-buggies, and has for its object to provide a new and improved construction by which the joints in the usual side braces of a buggy-top may readily be broken by the occupant 15 of the vehicle. I accomplish this object as illustrated in the drawings and as hereinafter described.

What I regard as new is set forth in the claims.

20 In the accompanying drawings, Figure 1 is a side elevation. Fig. 2 is a section on line 2 2 of Fig. 1. Fig. 3 is a perspective view of one of the corner-brackets. Fig. 4 is a sectional view illustrating the operating devices 25 by which the brace-joints are broken. Fig. 5 is a section on line 5 5 of Fig. 4. Fig. 6 is a perspective view illustrating the arrangement of the lever and the adjacent parts. Fig. 7 is a perspective view of one of the connecting-plates used in the construction 30 shown in the figures above referred to. Fig. 8 is a partial perspective view of the operating-lever which coacts with said plates. Fig. 9 is a perspective view illustrating a modification. Fig. 10 is a longitudinal sectional 35 view of the construction shown in Fig. 9. Fig. 11 is a perspective view of the connecting-plate used in the construction shown in Fig. 9, and Fig. 12 is a perspective view 40 showing a modified arrangement for connecting the braces with the operating-shaft in the construction shown in Figs. 9 and 10.

Referring to the drawings, 13 indicates the body of the buggy, 14 the seat-frame, and 45 the top, of which 16 17 are the usual braces jointed at 18 in the ordinary way.

50 19 indicates an operating-shaft which extends longitudinally of the seat-frame and transversely of the body of the buggy and is fitted in suitable bearings in ears 20, carried by corner-brackets 21 22, which are fitted in the corners of the seat-frame so that the ears 55 project slightly above the upper edge of

the seat-frame, as shown in Fig. 1, and are secured to the ends and back of the seat-frame, being provided with angularly-disposed wings or members 23^a 23^b for that purpose.

In the construction shown in Figs. 1 to 8 the ends of the shaft 19 are squared, as shown 60 at 23 24 in Fig. 4, and the braces 16 17 are provided with correspondingly-shaped sockets, which fit upon the outer end portions of said shaft. It will be understood that the term "squared" is used in a generic sense to 65 mean any shape non-circular in cross-section. As also shown in Fig. 4, the squared portion of one end of the shaft 19, preferably the left-hand end portion thereof, extends to a point near the ear 20, a shoulder 25 being 70 provided a short distance from said ear. The object of said shoulder is to provide a stop against which a connecting-plate 26 may abut, said plate being fitted upon the squared portion 23 so as to turn with said shaft. 75

Fig. 7 illustrates the construction of the connecting-plate 26, which, as therein shown, is provided with a hole 27, which corresponds in shape to the squared portion 22^a of said shaft. Said plate is also provided with a 80 projecting portion 28, preferably formed by cutting down the periphery of the lower portion of said plate. It may, however, be formed in any other suitable way, as by providing a lug at a suitable point on said plate. 85 Fig. 7 indicates the operating-lever, which is mounted on the rounded portion of the shaft 19 between the connecting-plate 26 and the ear 20. (Best shown in Fig. 4.) The lever 29 is provided with a laterally-projecting lug 90 30, which projects over the reduced portion of the plate 26 and is adapted to engage the projecting portion 28 thereof, as shown in Figs. 5 and 6. The arrangement is such that when the lever 29 is in a horizontal position 95 the lug 30 is in contact with the projecting portion 28 of the plate 26. Consequently by raising said lever the plate 26 is rocked, thereby rocking the shaft 19, and consequently 100 rocking back the braces 16 17 and breaking the joints 18. When the joints have been broken, the lever 29 may be employed to lower the buggy-top, or, if desired, it may be turned to its horizontal position without affecting the buggy-top. This construction is desirable, 105 since it permits the operating-lever to be re-

stored to its normal position when the buggy-top has been lowered. 31 32 indicate springs mounted on the end portions of the shaft 19 between the ears 20 and the braces 16 17, respectively. The inner end of each spring engages lugs 33, carried by the corner-brackets 21 22, as best shown in Figs. 3 and 4. A plurality of said lugs are provided for adjusting the tension of the springs. The outer ends 10 of said springs are connected to plates 34 35, respectively, mounted on the shaft 19 adjacent to the inner surfaces of the braces 16 17, respectively. Said plates are provided with squared openings, which fit upon the squared 15 portions 23 24 of said shaft, so that they turn with the shaft. The purpose of said springs is to assist in raising the buggy-top. Their arrangement is such that they are put under tension when the buggy-top is lowered. 36 20 indicates covering-sleeves, which are fitted over the springs 31 32 and fit between the plates 26 34 at one side of the buggy and between the ear 20 and the plate 35 at the other side. 37 indicates screw-caps which 25 are screwed upon the ends of the shaft 19 to hold the parts together.

In Figs. 9, 10, and 11 I have illustrated a modified construction, in which the operating-lever 38 is not provided with the lug 30 30 and is connected with the operating-shaft 39 by means of a connecting-plate 40, which is loosely mounted on the shaft 39 and is connected therewith through a notched plate 41, which is fitted upon the squared portion of 35 the shaft 39, so as to rotate therewith. This construction is best shown in Fig. 9. It will be noted that the connecting-plate 40 is provided with a lug 42, which extends over the upper edge of the lever 38 and engages one of 40 the notches in the periphery of the plate 41. This construction provides for adjusting the normal position of the operating-lever 38, which is accomplished by shifting the lug 42 from one notch to another of the plate 41. 45 The operating-shaft 39 further differs from the operating-shaft 19 in that the side braces are loosely mounted upon its outer ends and are connected thereto by connecting-plates 43, which are fitted upon the shaft 39, so as 50 to rotate therewith, and are provided with a laterally-projecting pin 44, which engages the adjacent side brace 45. In other respects the plates 43 correspond with the plates 34 35 of the construction illustrated in 55 Fig. 4. It will be noted that in the construction illustrated in Figs. 9 and 10 the ears 20 of the corner-brackets 21 22 lie next to the inner ends of the sleeves 36. If desired, instead of providing the plates 43 with pins 44 60 plates 46 may be used, having grooves 47, in which the side braces fit, or any other suitable means may be employed for connecting the side braces with said plates.

By the construction and arrangement of 65 the parts shown it will be evident that both

of the side braces must be moved simultaneously, thereby avoiding the racking and straining of parts which frequently accompany the operation of lowering a buggy-top by hand. The operating-lever may, if desired, be located at either side of the buggy, or levers may be provided at both sides; but it will generally be found more convenient to provide a single lever at the right-hand end of the seat, as illustrated in the drawings. 75

By my invention I am able to quickly equip any ordinary buggy with a top-lowering device that is simple, inexpensive in construction, and neat in appearance. By the use of seat corner-brackets, as illustrated and 80 described, a rigid support is provided for the operating parts and provision is made for regulating the tension of the lifting-springs.

It will be understood that while I have described in detail my improvements as illustrated in the accompanying drawings my invention is not restricted to the specific constructions described, except in so far as they are specifically claimed, but includes generically the subject-matter of the broader claims. 90

That which I claim as my invention, and desire to secure by Letters Patent, is—

1. In a vehicle, the combination of a seat, a folding top therefor, jointed braces for holding said top in position, a shaft with which the lower end portions of said braces are connected, the end portions of said shaft being squared, bearings in which the rounded portions of said shaft are fitted, a lever rotatably fitted upon said shaft, a disk non-rotatably fitted upon a squared portion of said shaft, and means coacting with said disk for connecting said lever with said shaft. 95

2. In a vehicle, the combination of a seat, a folding top therefor, jointed braces for said top, a rock-shaft with which the lower end portions of said braces are connected, apertured brackets secured to the seat, said shaft extended through and journaled in said brackets, a lever rotatably mounted on said shaft adjacent to one of said brackets, a disk non-rotatably mounted on said shaft adjacent to said lever, and means coacting with said disk for connecting said lever therewith when the buggy-top is in its raised position. 115

3. In a vehicle, the combination of a seat, a rock-shaft journaled thereon and having its ends projecting beyond the side edges of the seat, a folding top, jointed braces for holding said top in its raised position, the lower end portions of said braces being connected with said shaft, a lever for rotating said shaft, springs mounted upon the projecting end portions of said shaft, one end of each of said springs being connected with said shaft and the other end with a stationary support, and sleeves inclosing said springs, substantially as described. 120

4. The combination with a buggy-body and its movable top, of a shaft extending 130

across said body and having connected to it near its ends a pair of braces secured to said top, supports in which said shaft is axially movable, two plates, one of which is fixed and the other of which is loose on said shaft, said loose plate carrying a projection adapted to engage the fixed plate, and a lever adapted to be moved against said projection, substantially as described.

10 5. The combination with a buggy-body, and its movable top, of a shaft extending across said body and having connected to it near its ends a pair of braces secured to said top, supports in which said shaft is axially movable, a plate secured to said shaft so as to turn therewith and provided with a notched edge, a second plate loose on said shaft and provided with a lateral projection adapted to engage the notched edge of said first-named plate, and a lever for moving said plates, substantially as described.

6. The combination with a buggy-body and its movable top, of a shaft extending across said body and having connected to it near its ends a pair of braces secured to said top, supports in which said shaft is axially movable, a plate secured to said shaft so as to turn therewith and provided with a notched edge, a second plate loose on said shaft and provided with a lateral projection adapted to engage the notched edge of said first-named plate, and a lever loosely mounted on said shaft between said plates and adapted to be turned to strike against said projection, substantially as described.

35 7. The combination with a buggy-body and its movable top, of a shaft that is angular in cross-section at its ends and having mounted at its ends a pair of braces secured to said top, supports for said shaft having enlarged openings to permit the shaft to turn axially,

two plates one of which is fitted upon said shaft to turn therewith and the other of which is loose thereon, a projection carried by the loose-fitting plate and engaging the 45 fixed plate, a lever loosely carried on said shaft between said plates and adapted to be turned to strike against said projection, and connections between said shaft and pair of top braces to cause said braces to move with 50 the axial movement of the shaft, substantially as described.

8. The combination with a buggy-body and a movable top therefor, of a rock-shaft extending across said body, a pair of brackets 55 secured to said body, each of said brackets having a vertical ear through which said shaft passes and one or more notches on its outer face, a sleeve around said shaft beyond each of said ears, a coiled spring in each 6c sleeve, one end of each spring being held in one of the said notches on the adjacent bracket, top braces carried by and movable with the shaft, and a lever for rocking said shaft, substantially as described. 65

9. The combination with a buggy-body and its movable top, of a rock-shaft extending across said body, a bracket having an ear through which said shaft passes, a sleeve having one of its ends closed by said ear, and 70 having its other end closed by a plate that is carried by and turns with said shaft, a coiled spring within said sleeve, one end of said spring being secured to said bracket, a buggy-top brace mounted on said shaft, means carried by said plate for engaging said brace, a nut on said shaft, and a lever for rocking said shaft, substantially as described. 75
